ABSTRACT

A ski edge member with: a straight portion divided into a plural number of sections by longitudinally forwardly inclined slit-like cracks, and a web integral with the straight portion and extending horizontally from one side of said straight portion, the web having, in each region corresponding to a crack, a pair of grooves each having one end extending close to the straight portion and the other end being open so as to position the crack midway between the one ends of said pair of grooves. The web further has a connecting member for connecting adjacent ones of said sections flanked, via the pair of grooves, by reinforcing lugs and having an inner cutout at a site substantially on the extension of the crack and having an elongated slot surrounding the inner cutout. The crack is open into the elongated slot, and the connecting member further has a pair of resilient projections defined by the pair of grooves and the elongated slot and also a resilient flap portion defined by said elongated slot and said inner cutout and further having connecting portions connecting said resilient projections with said flap portion. Such an edge member can withstand sufficiently a high applied tensile load without impairing the flexibility of the ski body.

EDGE MEMBERS FOR SKI
BACKGROUND OF THE INVENTION

1. Field of the Invention:

The present invention pertains to edge members for skis, and more particularly it relates to edge members for skis such that they do not impair the flexibility of ski bodies.

2. Description of the Prior Art:

A ski is generally comprised of a ski body and a sho-
efastening means attached to the ski body. The ski
body is provided, longitudinally of the ski body, with
edge members made in general of steel for the purpose
of protecting the sole surface and for the purpose of
easily causing the lower lateral edge portion of the sole
to bite into the snow surface, which is the so-called edg-
ing performance, when it is intended to reduce the
speed during gliding. However, the ski body per se is
not rigid but resilient, rich in flexibility. In order to
maintain this resiliency, there have been many efforts
in the arrangement and design of the ski body. How-
ever, when edge members made of rigid steel are fixed
to the sole surface of a ski body, the initial resiliency of
the ski body is impaired, and the ski body equipped
with such rigid edge members will itself have an addi-
tional rigidity. Thus, the desired characteristics of the
resulting complete ski which has been produced with
great designing skill will be lost.

However, most skis cannot do without edge mem-
bers. For this reason, there are many great efforts in the
development of improved edge members which will not
reduce the resiliency of the ski body. Recently, there
have been introduced edge members called "cracked
edge members" each having a plurality of spaced slits
in the straight running portion to provide a plural num-
ber of straight sections. As compared with the prior
edge members each having a continuous straight por-
tion, the cracked edge members are constructed so as
not to substantially impair the flexibility of the ski
body.

As the cracked edge members which are either avail-
able now or known at present, there may be given the
following two types, one of which is the cracked edge
member described in Japanese Pat. Publication No.
45-6341 and the other is the cracked edge member dis-
closed in West German Utility Model No. 6905035
representing an improvement of the former. The for-
mer, however, has the problem that the edge member
is susceptible to breakage as the bending stress applied
to the edge member is concentrated in the portions
having cracks. The cracks have no advantage other
than that they do not impair the flexibility of the ski
body. It may be said that the cracks themselves even
contribute to making the edge member break more eas-
ily whenever a substantial tensile stress is applied to the
cracked portions. Therefore, efforts have been made to
improve edge members from the viewpoint also that
they have to be capable of coping with the tensile stress
applied thereto. However, the edge member disclosed
in said Japanese Pat. Publication No. 45-6341 employs
an arcuate element as the element that can resist a sub-
stantial tensile stress applied. It should be noted, how-
ever, that whenever a substantial tensile stress is ap-
plied to this arcuate element, the central part of this ar-
cuate element will quite easily yield.

When a person mounts on skis, those portions of
their soles located at the respective arch-bend regions

will be subjected to a marked pulling force. If, there-
fore, the edge members are unable to adapt themselves
to this stress applied, they will eventually break. How-
ever, in case this easily breakable portion of the edge
member is reinforced with a rigid element, then the
edge member having such a reinforced portion will no
doubt possess an excessively great strength against the
tensile stress applied, contributing to an increase in the
rigidity of the edge member. However, the flexibility or
resiliency of the ski body will be reduced greatly.

The aforesaid latter steel edge members disclosed in
the West German Utility Model have been proposed as
an improvement of the known edge members described
above. However, the edge members of this West Ger-
man Utility Model are too excessively resistant to the
tensile stresses applied so that they will not break even
when stresses are concentrated thereto and they have
an enhanced durability. These edge members, how-
ever, sacrifice the flexibility of the ski body.

In case a tensile load is applied to edge members be-
cause a person mounts on skis, the arch-bend regions
of these skis will be subjected to a bending load. Ac-
cordingly, the sole surface of each ski which is located
at a position lower than the center of the ski body will
have to support the tensile load applied. The ski body
as a whole also will undergo an extension to a slight de-
gree. Each edge member which is integrally attached to
the ski body will be caused to extend also. However, in
case the edge members employed are cracked edge
members, such an extension will be manifested as the
total of both the extension strain representing the wid-
ening apart of the respective slit-like cracks of the edge
member and the extension strain of the straight por-
tions of the edge member which are the portions that
unite together the respective sections divided by the
cracks. An edge member itself requires only a sufficient
rigidity. In the event, however, that the ski body is
caused to extend itself by the bending load applied, it
will be noted that, unless the edge members which are
arranged as integral parts of the ski body adapt them-
selves so as to exert an extension in conformity to the
extension of the ski body, there will naturally develop
staggering of positions between the edge members and
the ski body. Development of such staggering in position
of these parts of a ski, in turn, will very undesirably
result in either the detachment of the edge members
from the ski body or the impairment of the flexibility
of the ski body. Thus, if the edge members are made of
a material, such as rubber, which can extend in confor-
mity with the extension of the ski body, there will de-
velop no staggering in position between the edge mem-
bers and the ski body nor will there arise any impair-
ment of the flexibility of the ski body. However, in real-
ity it is impossible to find a material which meets the
aforesaid requirements as edge members of a ski.

In order to solve the aforesaid problems where the
material of edge members is limited at present to steel,
there must be developed a device to provide edge
members having a somewhat lessened rigidity. If the
straight portion of a steel edge member is provided with
a number of closely positioned cracks throughout its
length, such an edge member would surely possess a
great adaptability to the deformations developed by the
ski body. However, such a cracked edge member will
possess no desired strength and accordingly this edge
member will never be suitable for use.

It is the aforesaid known edge member that has been designed with the aim of imparting thereto both an adaptability to the ski body and a desirable strength under the restriction in term of material that the edge member has to be made of steel. In such a known edge member, it would be ideal if this edge member functions in such a way that, whenever the edge member is caused to extend owing to the tensile stress applied to its entire length, the gaps of the slit-like cracks will become widened apart, causing the edge member to exert an extension, without any resistance, in conformity with the extension of the ski body. However, in reality the straight portions which serve to connect the divided sections together possess a rigidity and impair the flexibility of the ski body.

SUMMARY OF THE INVENTION

It is, therefore, a primary object of the present invention to provide an edge member made of steel, which is much closer to an ideal edge member as compared with the aforesaid two types of edge members of the prior art.

Another object of the present invention is to provide a cracked edge member of the type described, which is not too rigid as would decrease the operability in attaching it to a ski body nor so rigid as would hamper the bending deformation of the ski body but can sufficiently cope with the widening of the gaps of the cracks whenever a substantial tensile stress is applied thereto.

BRIEF DESCRIPTION OF THE DRAWINGS

FIG. 1 is a perspective view of a part of an L-shaped edge member embodying an example of the present invention.

FIG. 2 is a bottom plan view of the same part of FIG. 1.

FIG. 3 is a perspective view of a part of the same edge member of FIG. 1 but shows the repetition of the pattern of the connecting members and reinforcing lugs both of which form a part of the edge member of FIG. 1.

FIG. 4 is a bottom plan view similar to FIG. 2, showing a modified example of the essential part of the edge member according to the present invention.

FIG. 5 is a similar view, showing still another modified example.

FIG. 6 is a cross section of a ski to show how the edge members of the present invention are attached to the ski.

FIG. 7 is a diagrammatic fragmentary side view of a part of the straight portion of an edge member according to the present invention to show an inclined slit-like crack.

DETAILED DESCRIPTION OF PREFERRED EMBODIMENTS

The present invention will hereunder be described on some preferred embodiments by referring to the accompanying drawings which are given only by way of example.

By referring to FIGS. 1 through 3, there is shown a part of a first example of the L-shaped cracked edge member according to the present invention. This edge member shown generally at A is made of steel and is to be provided on a ski body in the longitudinal direction thereof. The straight portion of the edge member A which is indicated generally at 1 is of a substantially

square cross section. A web 2 having its upper surface positioned at the same plane with that of the upper surface of the straight portion 1 and having a thickness which is about one third of the vertical height of the straight portion 1 extends horizontally from a lateral side of the straight portion 1 for the entire length thereof.

This straight portion 1 is provided with slit-like cracks 11 which are disposed at constant intervals. Each of these cracks 11 is inclined in such a way that its upper portion is positioned closer toward the shovel portion of the ski and its bottom portion is positioned closer toward the tail of the ski relative to the running direction X of the ski, as shown in FIG. 7. Depending on the type of ski and on the material with which the edge member is made, the intervals between the cracks 11 are in the range of, generally, 2 to 3 cm.

The web 2 has a plural number of connecting members indicated generally at 21 and reinforcing lugs generally indicated at 22. This connecting member 21 has an elongated slot 21a which is of a substantially semi-circular arcuate configuration having its center C located on the extension L of the slit-like crack 11. The crack 11 is extended toward the center C so that the crack is open into the slot 21a. That portion of the connecting member 21 containing the center C is provided in the form of a substantially U-shaped inner cutout 21b of a substantial width in the radial direction of the aforesaid arcuate slot 21a and having substantially parallel legs of U-shape and having a rounded closed bottom of said U-shape so that the end edge of the connecting member 21 in the portion which is away from the straight portion 1 is open. Between the connecting member 21 and a reinforcing lug 22, there is provided a groove 23 which is arcuate in configuration concentric with the semi-circular elongated slot 21a. This arcuate groove 23 extends at its one end toward the inner side of the straight portion 1 in such a way that this one end terminates as a closed end with a small interval from said inner side of the straight portion 1. In addition, this closed end of the arcuate groove 23 which is located on the straight portion 1 side is positioned closer to the slit-like crack 11 which is formed in the straight portion 1.

The reinforcing lug 22 is formed between two arcuate grooves 23 and 23. This reinforcing lug 22 is provided, at a central portion, with an opening 22a for the purpose of enhancing the adhesivity of the edge member A to the component members of the ski body by allowing an adhesive to be applied in this opening 22a to be filled therein. This reinforcing lug 22 has flexibility because of its opening 22a.

Within each pitch between the adjacent slit-like cracks 11 and 11 is disposed one connecting member 21 and one reinforcing lug 22, respectively. The connecting member 21 is such that it is locally cut away at the semi-circular elongated slot 21a and at the inner cutout 21b. This inner cutout 21b has a closed end edge 21'b which is round in configuration and concentric with the semi-circular elongated slot 21a. The ends of this round closed end edge 21'b have extensions 21''b and 21'''b which are rectilinear and form parallel legs of U-shape having an open other end. The connecting member 21 corresponding to a crack 11 is rendered as a continuous member longitudinally of the edge member A by a solid part or flap 21A which is semi-circular and flexible and located on the proximal center side of

the semi-circular elongated slot 21a. This semi-circular flap 21A is not of a wave-like shape. The proximal edge is shaped to have a round edge by the aforesaid inner cutout 21b having a considerable depth. Along therewith, this semi-circular flap 21A gives a basis for the general contour of the connecting member 21. Moreover, the outer peripheral solid portion or projection 21B of the semi-circular elongated slot 21a has a breadth similar to that of the semi-circular flap 21A and an arcuate shape which is substantially concentric with this semi-circular flap 21A. Thus, this portion 21B is provided as a flexible element. One end of the outer peripheral solid portion or projection 21B joins the straight portion 1 of the edge member A. The arcuate groove 23 in this example is not perpendicular to the length of the edge member 1 nor is it of a wave-like shape as will be clear from the foregoing statement. This arcuate groove 23 is provided so as to extend, in the form of a substantially concentric arc with respect to the arcuate slot 21a until it terminates shortly before joining the straight portion 1, thus rendering both the reinforcing lug 22 and the connecting member 21 independent of each other.

Next, description will be made on the actual deformation which the skis having the aforesaid edge members will undergo when mounted by a user.

In case these skis are not mounted by a person, each ski retains its initial so-called "arch-bend," i.e. the form of the central part of the ski which is warped in an arch-like bent form. Whenever a substantial bending load is applied to the ski from thereabove, this arch-bend becomes depressed or sunken a little, causing a tensile stress to develop at the surface of sole. Corresponding to this tensile stress, the edge members of the ski also will be subjected to a tensile load.

In such a case, the gaps of the respective slit-like cracks of each edge member will become widened apart and accordingly the edge member will develop an extension corresponding to the tensile stress applied thereto. The widening of the gap of crack 11 will bring an effect in the web 2 such that the semi-circular flap 21A of the connecting member 21 will extend longitudinally of the edge member A and this edge member as a whole will accordingly develop an extension due to the tensile load applied. This tensile load, when applied to the edge member, is supported by the semi-circular flap 21A and the outer peripheral solid portion or projection 21B, in such a manner that one half of this load is borne by one of these two elements 21A and 21B, respectively. As a result, this edge member A is able to withstand a load which is twice as great as the load which could be borne by a conventional edge member.

In other words, the degree of extension which can be exerted by the connecting member 21 is extremely great as compared with that exerted by the straight portion 1 of the edge member. Even in case the gap of the crack is widened substantially, the connecting member 21 is able to develop a lengthwise extension to sufficiently cope with this widening of the crack. This absorption of extension by the connecting member 21 is materialized by the fact that this connecting member 21 which connects those divided sections of the straight portion 1 of the edge member A which are rendered to severed state by the provision of cracks is of such a configuration as giving a great allowance for an extension by the cooperation of the semi-circular elongated slot 21a surrounding the semi-circular flap 21A and the

inner cutout 21b provided in a radial direction of the elongated slot 21a. Especially, the connecting member 21 which faces the crack 11 is of a configuration whose solid regions each has a small breadth, and also the arcuate grooves 23 and 23 which are provided on the outer sides of the connecting member 21 are each of such an arcuate configuration extending at one ends toward the slit-like crack 11. Accordingly, when compared with known cracked edge members, it is possible to expect markedly great elasticity from the edge members of this example of the present invention.

FIG. 4 shows another embodiment which shows a modification of especially the configurations of the connecting member 221 and of its surrounding grooves 223. In this example, the connecting member 221 generally has a somewhat rectangular configuration. More specifically, the connecting member 221 has an elongated slot 221a which is of a substantially U-shaped configuration in which both legs of U-shape are substantially symmetrical relative to the extension of the slit-like crack 11. That portion of the connecting member 221 corresponding to the inner cutout 21b of FIG. 2 is provided as an inner cutout 221b having a substantially U-shaped configuration but having a rather flat closed bottom 221'b of U-shape. Therefore, the solid part 221A is of a generally U-shaped configuration having a rather flat bottom of U-shape. Moreover, the outer peripheral projection 21B of FIG. 2 is provided, in this example of FIG. 4, in the form of generally a straight projection as shown at 221B. The arcuate groove 23 of FIG. 1 is provided, in this example of FIG. 4, in the form of a generally straight U-shape groove; 223 having a generally flat bottom of U-shape having substantially parallel legs of U-shape. Both of these elements 221A and 221B are resilient as in the preceding first example. The reinforcing lug 222 having an opening 222a is substantially similar to the flexible reinforcing lug 22 of FIGS. 1 and 2 excepting for the substantially straight edge line adjacent to the groove 223. The flexible outer peripheral projection 221B and the flap 221A which is contiguous to the projection 221B jointly cooperate in withstanding a deformation stress applied to the edge member A' having these elements 221B and 221A.

FIG. 5 shows a still another embodiment. In this embodiment, the connecting member 321 has a generally one longitudinal half of an oval shape. This connecting member 321 has an elongated slot 321a which is of an oblong configuration defined between two lines each being substantially one half of an oval shape, and this slot 321a is substantially symmetrical relative to the slit-like crack 11. The inner cutout 21b of FIG. 2 is provided, in this example of FIG. 5, as an inner cutout 321b having a configuration which is a substantially one longitudinal half of an oval shape with its apex which is closer to the straight portion 1 being rounded and with its opening being widened because of the curved extensions 321'b of edges of the leg portions of a wide U-shape inner cutout 321b. Therefore, the flexible flap 321A is of a substantially one longitudinal half of an oval shape. The groove 323 is of a configuration as shown in FIG. 5, forming an elongated flexible projection 321B as shown. The flap 321A is contiguous with the projection 321B and they cooperatively resist any deformation stress applied to the edge member A''.

In each of the respective embodiments of FIGS. 4 and 5, the patterns of the connecting member and the

adjacent reinforcing lug are to occur repeatedly in the same manner as shown in FIG. 3 which represents the first example.

In each of the last two examples, the cracks 11 are open into the elongated slot 221a or 321a and are each 5 provided so as to be inclined with its upper end closer to the shovel portion of the ski in the same manner as described in connection with the first example.

As shown in FIG. 6, the edge members A according to the present invention are provided on both sides of 10 the ski body. Reference numeral 24 represents the top surface member of a ski, 25, core members, 26, side members, and 27, the bottom or sole member of the ski. The edge members A of this invention are fixedly secured between the bottom and core members. Top 15 edge members 28 may be provided at the upper parts of the ski.

As has been stated, according to the present invention, a ski is provided with an appropriate number of slit-like cracks. Because of these cracks, the edge members are not of such a rigidity as would decrease the sound efficiency of attaching them to the ski body or would hamper the bending deformation of the ski body. Besides, the edge member as a whole can sufficiently 20 accommodate the widening of the cracks whenever a tensile load is applied to the edge member. Thus, an ideal edge member is obtained.

I claim:

1. An edge member for a ski, comprising a straight portion and a web extending horizontally from one side 30 of said straight portion,

said straight portion being divided into a plural number of sections by slit-like cracks,

said web having, in each region corresponding to a crack, a pair of grooves each having one closed end 35

located close to the straight portion and an open other end, said pair of grooves being positioned so that the crack is intermediate the closed ends of said pair of grooves,

said web further having, in each said region, a connecting member for connecting adjacent ones of said sections of the straight portion, said connecting member being flanked, via said pair of grooves 40

25

35

40

and, by reinforcing members, said reinforcing members forming the portion of the web between successive pairs of grooves.

said connecting member further having, at a site substantially corresponding to the extension of said crack, an inner cutout with one closed end and open other end and an elongated slot surrounding this inner cutout, said crack being open into the elongated slot,

said connecting member further having a pair of resilient projections defined by said pair of grooves and said elongated slot; a resilient flap defined by said elongated slot and said inner cutout; and connecting portions for connecting said resilient projections with said flap.

2. An edge member according to claim 1, in which said elongated slot is substantially semi-circular in configuration, and said closed one end of the inner cutout has a round bottom edge concentric with said semi-circular elongated slot, and said pair of grooves are each substantially concentric with said semi-circular elongated slot.

3. An edge member according to claim 1, in which said elongated slot is substantially U-shape in configuration with the legs of U-shape being substantially parallel with each other, and said inner cutout is substantially U-shape with its legs of U-shape extending substantially parallel with the legs of said elongated slot and its closed bottom has a substantially flat edge, and said a pair of grooves each has a substantially U-shape with its closed bottom having a substantially flat edge and its legs of U-shape extending substantially parallel with the legs of said elongated slot, the entire connecting member thus having a generally rectangular configuration.

4. An edge member according to claim 1, in which said elongated slot is of a configuration substantially one longitudinal half of an oval shape, and said inner cutout is of a configuration substantially one longitudinal half of an oval shape, and said a pair of grooves each has a configuration for defining the curved outer peripheral part or projection of the elongated slot.
